UNITED STATES PATENT OFFICE.

DANIEL E. REAGAN, OF COLUMBUS, OHIO, ASSIGNOR TO HOCKING VALLEY PRODUCTS COMPANY, OF COLUMBUS, OHIO, A CORPORATION OF WEST VIRGINIA.

ORNAMENTAL BRICK.

1,118,681.

Specification of Letters Patent. Patented Nov. 24, 1914.

Application filed May 22, 1914. Serial No. 840,347.

To all whom it may concern:

Be it known that I, DANIEL E. REAGAN, of Columbus, in the county of Franklin and State of Ohio, have invented certain new and useful Improvements in Ornamental Bricks; and I do hereby declare the following to be a full, clear, and exact description of the invention, such as will enable others skilled in the art to which it appertains to make and use the same.

My invention relates to an improvement in ornamental bricks, the object being to produce a brick the face and ends of which are roughened to produce a rough textile, or rug effect.

In the accompanying drawings, Figure 1 is a view in perspective of a brick embodying my invention, and Figs. 2 and 3 represent sections of the clay slab showing the different steps in the manufacture of the brick.

In the method employed in the production of the "rug" brick, which is the trade term by which these particular bricks of my manufacture are now known, the clay or composition from which the brick is made, is thoroughly worked and forced through a die of a stiff-clay machine in the form of a continuous mass rectangular in cross-section, the mass being subsequently cut into brick size by wires or other suitable cutting devices in the well known manner. After the clay or composition mass passes from the die, and while in a plastic condition, the upper face of the mass and the two sides thereof, are roughened by scratching, furrowing or scoring the surface of the mass as shown in Fig. 2, leaving the body of the plastic mass intact, and of the same density as it was before the said surfaces were acted upon. The strips or particles of the mass thus loosened, are more or less detached from the body of the same, and are then subjected to devices which operate the spread and distribute the strips or particles of clay in a confused or unsymmetrical layer across the faces of the mass as in Fig. 3 so that no two bricks will be exactly alike, and consequently

will not present the sameness in appearance as molded brick, or brick roughened by the imprint of a die or cutting wire. After the strips or particles of the mass thrown up by furrowing, or scoring the faces of the mass have been spread out, in a confused or tangled layer evenly over the faces, the latter are subjected to a pressure sufficient to smooth off the surfaces and to cause the loosened particles to mat together and adhere firmly to the body of the brick, without destroying the "rug" effect of the surfaces.

I prefer to roughen the surfaces by parallel furrows in the direction of movement of the moving mass of clay as it leaves the die of the brick machine, so that they will be vertical when the bricks are placed in a wall, and thus provide for drainage. Again instead of roughening the surfaces of the clay mass before the latter is severed into blocks or bricks, the cutter may be intermediate the die and the roughening means. Again instead of treating three faces of each brick, some bricks may have only one face roughened and others one end, as it is only necessary that the exposed face or end be roughened.

Having fully described my invention what I claim as new and desire to secure by Letters-Patent, is:

1. As an article of manufacture a brick having a roughened face of rug like texture, the said face being characterized by parallel furrows, the said furrows being more or less obliterated by a distribution of the material furrowed up.

2. A brick provided in its face with parallel furrows the material separating the furrows being distributed over the latter so as to partly obliterate the same.

In testimony whereof, I have signed this specification in the presence of two subscribing witnesses.

DANIEL E. REAGAN.
